United States Patent Office.

JOHN H. KAPPELHOFF AND SAMUEL RAUH, OF NEW YORK, N. Y.

Design No. 4,179, dated June 28, 1870.

DESIGN FOR A FUR COLLAR.

The Schedule referred to in these Letters Patent and making part of the same.

To all whom it may concern:

Be it known that we, JOHN H. KAPPELHOFF and SAMUEL RAUH, of the city, county, and State of New York, have invented a new and original Design for Fur Collar; and we do hereby declare the following to be a full, clear, and exact description thereof, which will enable those skilled in the art to make and use the same, reference being had to the accompanying drawing forming part of this specification, which drawing is a front view of our collar.

Our invention relates to a new design for a fur collar, which is provided with triangular incisions, and with breast-flaps of a peculiar form, said breast-flaps being ornamented by false flaps, and the entire collar being provided with a border, whereby an elegant and distinguishing appearance is imparted to the same.

In the drawing, the letter A designates a fur collar, which is cut out so as to form triangular incisions, *a*, at the junction, between the back flap *b* and the breast-flaps *c*.

The back flap is formed with points *d*, and the breast-flaps with points *e*, and the outer edges of said breast-flaps are ogee-shaped, as shown.

The breast-flaps are ornamented by false flaps, *f*, and the entire collar is provided with a border, *g*.

What we claim as new, and desire to secure by Letters Patent, is—

1. The design for a fur collar, having points *d* *e*, and intervening incisions *a*, as shown and described.
2. The ogee-shaped edge of the breast-flaps, as shown and described.
3. The false flaps *f* on the breast-flaps, formed as shown and described.

JOHN H. KAPPELHOFF.
SAMUEL RAUH.
